UNITED STATES PATENT OFFICE.

ROLAND C. PINDER, OF LIMA, OHIO.

TONE-MODIFYING DEVICE FOR PIANOS.

Application filed September 14, 1921. Serial No. 500,546.

To all whom it may concern:

Be it known that I, ROLAND C. PINDER, a citizen of the United States, residing at Lima, in the county of Allen and State of Ohio, have invented certain new and useful Improvements in Tone-Modifying Devices for Pianos, of which the following is a specification.

This invention relates to improvements in tone modifying devices for use upon pianos and the like.

The primary object of the invention is the provision of an attachment for use upon pianos whereby the natural tone thereof may be modified to simulate the tone of a ukulele or the like.

A further object of the invention is the provision of a novel attachment for use upon pianos, which can be used as an accessory thereon, interfering in no manner with the standard equipment of the piano and capable of easy regulation to selectively change the tone of a piano, simulating the playing of other string instruments.

25 A further object of the invention is the provision of an attachment of the above described character, in which the parts thereof have been made detachable and adjustable to conform to the details of different makes of pianos.

30 A further object of the invention is the provision of a tone modifying element, constructed of special materials, and adapted for disposition intermediate a treble string and hammer of a piano to function in the piano action, whereby vibrations of the string will cooperate with the tone modifying member to simulate the tone obtained from vibration of a ukulele string.

40 Other objects and advantages will be apparent during the course of the following detailed description.

In the accompanying drawings, forming a part of this specification, and in which similar reference characters designate corresponding parts throughout the several views.

Figure 1 is a cross sectional view of the upper portion of a piano, showing the attachment mounted therein.

Figure 2 is a front elevation, in cross section, of the working arrangement of the attachment in a piano.

55 Figure 3 is a bottom plan view of the regulating means used in connection with the attachment.

Figure 4 is an enlarged perspective view of several working details of the attachment.

Figure 5 is an enlarged fragmentary perspective view of details of the attachment.

Figure 6 is a cross sectional view taken through a tone modifying member and showing its supporting means.

Figure 7 is a cross sectional view taken on the line 7-7 of Figure 4.

In the drawings, wherein for the purpose of illustration is shown the preferred embodiment of my invention, the letter A designates a piano of any approved type, having the ukulele attachment B mounted therein.

The piano A may of course be of the upright, grand, or player type. For purpose of illustration the upright type of piano has been shown, and which includes the casing 10; tone board 11; vertically positioned strings 12; and key board 13.

The ukulele attachment B preferably comprises the supporting bracket structures 15; supporting rail structure 16; control cable 17; tone modifying means 18; and regulating means 19.

The supporting bracket structure 15 comprises a pair of substantially U-shaped bracket elements 20, each of which includes an upper arm 21, a lower arm 22, and a connecting or bight portion 23. The bight portion 23 is provided with a plurality of apertures 24, adapted for receiving screw elements 25, for attachment of the bight portion 23 of the brackets 20 to the opposite sides 26 and 27 of the piano casing 10. The brackets 20 are of course, positioned in co-operating relation upon the sides 26 and 27, and in such manner that the arms 21 and 22 project inwardly of the piano. Suitable apertures are formed in the free ends of each of the arms 21 and 22 for the reception of the reduced stems 29 of a guide rod or shaft 30. Buffer elements 31, preferably discs of felt padding, are placed about the guide rods 20 and immediately upon the inside surface of the lower arm 22 of each bracket 20.

The supporting rail 16 includes the end strips or blocks 33 of similar formation, and having transverse apertures 34 extending through the width thereof and for receiving the guide rods 30. A treble strip 35, and a bass strip 36, are connected in offset parallel relation as by the screw elements 37, the ex-

treme ends of each of the strips 35 and 36 being seated within recesses 38 in the end pieces 33, and for connection by detachable screw element 39 thereto. Thus, when the 5 end portions 33 and intermediate treble and bass sections 35 and 36 are connected as above described, they comprise a longitudinal rail member. The apertures 34 are disposed inwardly from the extreme end of the 10 end portions 33, to provide a portion of the strip 33 upon each end of the rail member 18, which projects inwardly of its guide rod 30 and is provided with a relatively small aperture 40 through the thickness thereof. 15 Adjustable and detachable lock screw and washer structures 41 are disposed adjacent the apertures 40 and intermediate the same and the rods 30, and for a purpose to be subsequently described.

20 The modifying means 18, preferably comprises the felt strip 43 for use in connection with the bass strings of the piano scale, and the individual modifying members 44 for use in connection with single strings of the 25 middle and end sections of the treble scale. The surface 45 of the rail 16 which faces the key board of the piano A, is provided with three lengths of wire 47, one for each section of the piano scale; said wires 47 being detachably supported at their ends between spaced pins or nails 49, which are attached in the rails 16 to project from the 30 surface 45 thereof. The bass felt section 43 is slotted, in suitable manner along its upper marginal edge for threading a supporting wire 47 therethrough, whereby the same may be pendently hung from the wire 47 and the rail 16. As is clearly shown in Figure 35 2, this lower bass felt strip 43 covers all of the bass strings of the piano scale.

40 Each one of the treble tone modifying members 44 are of similar construction, the body portion 50 thereof preferably being a strip of flannel or other flexible material, and having a disc shaped leather tip 51 secured to an extreme end and upon one side thereof as by any suitable means 52. The opposite end of the strip of material 50, is provided with a substantially W-shaped 45 hook member 53, of some soft metal, such as tin, zinc, copper or the like. This hook member 53 crimps the end of the strip 50 between adjacent flanges thereof, to provide a hook 54 of the remaining flanges, whereby 50 the same may be crimped in detachable and adjustable manner over a supporting wire 47 on the rail 16. Since the wires 47 of the treble section of the piano scale are detachable, the tone modifying elements 44 may, of course, be hooked thereover and adjusted 55 into position, to conform to the individual strings of the treble scale. This is an important feature, since many piano scales have the strings thereof at varying distances. 60 In this manner, the leather tipped portions

51 of the members 44 are pendently held to face the strings of the piano scale.

In connection with the sliding movement of the rail 16, a pulley block 56 is provided, having an end thereof bifurcated to provide 70 the stems 58 and 59, projecting therefrom, whereby a device pin 60 may be disposed transversely through said stems 58 and 59, and which is for reception of the flexible control cable 17. If desired, a pulley sleeve 75 61 may be placed over this shaft or dial pin 60, whereby the same acts as a pulley to more readily permit sliding of the regulating cable 17. The pulley block 56 is provided with suitable apertures 63 therein, for 80 detachably receiving screws 64 for supporting the pulley block 56. The screws 64 are adapted for sliding movement within the slot 65 placed longitudinally of the arm 21 of each bracket 20. This slot 65 is disposed 85 adjacent one edge of the arm 21, and whereby when the block 56 is assembled thereto, the arm 59 thereof projects outwardly from the marginal edge of the bracket 20.

The flexible cable 17, is preferably of 90 braided dark green curtain cord, and may be of a single length. In applying the cable 17, the same is doubled intermediate its ends, and fastened to the eye 65 of a link member 66, said link 66 forming a part of 95 the regulating means 19 to be subsequently described.

From its connection with the eye 65, the two parts of the cable 17 are strung through an eye bolt 67, which is attached on the 100 inside surface of the piano side 27. From the eye bolt 67, the doubled cable 17 is swung upwardly over the pulley sleeve 61 of a pulley block 56, in a vertical manner. One end 69 of the cable 17, which is swung over the pulley block 56 is then brought downwardly, in vertical manner, and strung through the aperture 40, which is on the end of the rail 16, adjacent the piano side 27. The extreme end of this portion 69, of cable 17, is looped back over the portion 69 and clamped in the lock screw and washer device 41 for properly supporting one end 110 of the rail 16. The other portion 70, which is looped over the pulley block 56 is strung 115 in taut manner parallel of the rail 16, and engages over the pulley block 56 of the bracket 20 which is attached to the piano side 26, and looped in similar manner as the portion 69, through the end of the rail 120 16, which is adjacent the piano side 26. It can readily be seen that if a person pulls on the flexible cable 17, where the same is doubled, this will have the effect of causing the ends 69 and 70 of said cable 17 to ride 125 over the pulley blocks 56, to raise the rail 16.

The regulating mechanism 19 preferably comprises the supporting block 75 having the bell crank lever 76 pivotally mounted by a detachable screw 77 at the right portion 130

of its arms 78 and 79. The free end of the arm 78 is apertured for the pivotal reception of one end of the link element 66, above mentioned, said end being the end 5 opposite the eye 65 thereon. The arm 79 is provided as the finger engaging arm and is provided with a knob 80 thereon. The regulating mechanism 19 is attached in detachable manner by the screw elements 81 10 to the under surface 82 of the piano keyboard 13, and adjacent the right hand side of the piano. A stop screw or pin 83 is provided in the board 75 for engaging the hand engaging arm 79 for holding the link member 66 and its adjacent connecting portion of the cable 17 past dead center of the bell crank 76, when said regulating means 19 is adjusted to support the rail 16 in floating manner, and as illustrated in Figures 2 and 20 4 of the drawings. When the bell crank 76 is oscillated upon a pivot 77, whereby the same assumes the position shown in dotted lines in Figure 3 of the drawings, the cable 17 is released, whereby the dead center position 25 is passed and the cable 17 is released sufficiently to lower the frame 16, whereby the under surface thereof contacts upon the buffer members 31.

It is preferred, that the attaching wires 30 47, and the tone modifying members 43 and 44 supported therefrom, be clamped in rigid secure manner to the rails 16. To this end, the clamping strips 80^a have been provided, having a longitudinal groove 81^a extending 35 upon the inside face 82^a thereof, and which is adapted for receiving the wires 47 and the hooked elements 53, to secrete the same therein. Detachable screws 83^a are provided, engaging transversely through the clamp 40 members 80^a and for engaging in the rail 16, to support the tone modifying elements 43 and 44 in their adjusted position and against lateral displacement with respect to the strings of the piano scale.

45 In operation, when desiring to use the piano with the ukulele attachment, whereby the strings on the piano scale will simulate ukulele playing, the operator or player grasps the thumb portion 80 of the bell crank 76 and swings the same to the position indicated in dotted lines, whereby, as above mentioned the rail 16 is lowered in the supporting brackets 20. This lowering 50 of the rail 16 has the effect of likewise lowering the tone modifying members 43 and 44, whereby the same are placed intermediate the strings of the scale and the hammer heads 85. As the player strikes the keys (not shown) of the piano, the ordinary piano 55 action takes place, whereby the hammers 85 are thrown forward to hit the strings 12 of the piano. Due to the interpositioning of the tone modifying elements 43 and 44, the hammers 85 will strike the same and 60 force the same into contact with the string

12 for vibrating them, said tone modifying elements 43 and 44 cooperating with the vibrating strings 12 to simulate ukulele playing. Due to the fact that the leather elements 51 are provided for contact with the string 12, an almost perfect representation 70 of ukulele playing is effected. This is mainly due to the fact that the leather tip is just hard enough and yet of sufficient resiliency to prevent a metallic sound, and resembling as it does, the soft playing 75 muffled tone of a ukulele; differing in this respect from the ordinary mandolin tones.

When the player desires to use the piano in the ordinary manner without ukulele attachment B, the bell crank 76 is thrown in such a manner that the link 66 assumes the dead center position illustrated in full lines in Figure 3, and whereby the flexible cable 17 is drawn taut to lift the rail 16 in vertical 80 manner, the same being guided by the guide rods 30, whereby the tone modifying elements 43 and 44 are drawn upwardly out of the path of the movement of the hammers 85, and whereby said hammers 85 may contact directly on the strings 12, as in ordinary piano playing.

An important feature of this invention is the adjustability and detachability of all parts, whereby the same may be sold as an 90 accessory for attachment, in almost universal manner, to pianos. The pulley blocks 56 have been made adjustable in the supporting brackets 20, whereby the portions 69 and 70 of the flexible cable 17, may assume an 100 exact vertical position, when lifting the rail 16 to prevent tipping or swinging of the same. The exact horizontal position of the rail 16, can of course, be maintained by adjustability of the flexible cable 17, as effected through the lock screw and washer arrangements 41. The elements 43 and 44 are of course adjustable and detachable, as above described.

Various changes in the size, shape and arrangement of parts may be made to the form of invention herein shown and described, without departing from the spirit of the invention or the scope of the claims.

I claim:

1. A piano attachment, comprising a pair of substantially U-shaped brackets, guide rods mounted in said brackets, a rail, tone modifying means on said rail, adjustable pulley blocks on each of said brackets, a flexible cable engaging over said pulley blocks and secured to said rails, and regulating means for adjustment of said flexible cable to raise and lower the rail.

2. A device of the class described, comprising a rail, tone modifying means on said rail, brackets for slidably mounting said rail, a flexible cable attached at the ends of the said rail, and control means engaging said cable intermediate the ends thereof for 130

operating to reciprocate the rail on said brackets.

3. A device of the class described, comprising a rail, tone modifying means on said rail, supporting brackets for slidably mounting said rail, a flexible cable engaging said rail, and adjustable pulley blocks mounted in said brackets for receiving said cable whereby the same may support the rail in a defined relation.

4. A device of the class described, comprising a pair of substantially U-shaped brackets including arms and a bight portion, guide rods engaging the free ends of the arms of said brackets, a rail having apertures transversely therethrough in each end for receiving the guide rods of said brackets, said rail having each end portion projecting inwardly from the guide rod and toward the bight portion of its adjacent bracket, tone modifying means on said rail, and control means including a flexible cable engaging the ends of said rail for regulating reciprocatory movement thereof in said brackets.

5. A device of the class described, comprising a pair of substantially U-shaped brackets including arms and a bight portion, a guide rod engaged in the free ends of the arms of each of said brackets, a rail having apertures transversely therethrough in each end for receiving the guide rods of said brackets, said rail having each end portion projecting inwardly from the guide rod and toward the bight portion of its adjacent bracket, tone modifying means on said rail, a flexible cable engaging the free ends of said rail, buffer elements on said guide rods to receive said rail thereon, adjustable pulley blocks in each of said brackets to receive said cable thereon for vertical movement of said rail, and control means for operating said flexible cable to entirely support the rail in a set portion.

6. A musical instrument attachment comprising a supporting rail, tone modifying means, means supporting said tone modifying means on said rail for lateral adjustment thereon, and clamping means for securely fastening said tone modifying means on said rail in a fixed position.

7. In a device of the class described, the combination with a piano including bass and treble strings, and a piano action, of a rail, means mounting said rail for movement relative to the strings, tone modifying elements mounted on said rail for cooperation with said treble strings, and tone modifying means for said bass strings different from said treble string tone modifying means.

8. In a device of the class described, the combination with a piano including bass and treble strings, of a rail mounted in slideable manner therein, and including sections connected together in parallel relation and offset with respect to each other, a plurality of wires detachably mounted upon said rail sections, tone modifying members for the individual treble strings of the piano scale for adjustable and detachable arrangement on said wires, and a single adjustable and detachable tone modifying member mounted on one of said wires for the bass strings of the piano scale.

9. A tone modifying member comprising a flexible body, a leather tip exteriorly upon one end thereof, and a substantially W-shaped metallic hook of easily bent material crimped upon the other end of said flexible body.

10. In a tone modifying device for pianos the combination with a piano including bass and treble strings, of an elongated rail member, a length of flexible material supported by a portion of said rail member, a series of individual separate tone modifying members carried by the remaining portion of said rail member, and means mounting said rail member with respect to the bass and treble strings so that the length of flexible material may cooperate against the bass strings and the tone modifying members may cooperate against the individual treble strings.

11. In a tone modifying device for pianos the combination with the bass and treble strings of a piano, of elongated rail, a strip of felt supported by the rail in adjustable relation therewith, a series of flexible modifying members carried by said rail in adjustable relation therewith, means to clamp the tone modifying felt strip and series of members in a set position upon the rail, and means mounting the rail with respect to the bass and treble strings so that the strip of felt may cooperate against said bass strings and the series of flexible tone modulating members may cooperate against the individual treble strings.

12. In a device of the class described, the combination with a piano including bass and treble strings, and a piano action, of a rail, means mounting said rail for movement relatively to the strings and piano action, wires carried longitudinally on said rail, tone modifying members detachably supported by said wires for adjustment along said rail, and a clamping member carried by said rail adapted to secure said tone modifying members in a fixed position.

ROLAND C. PINDER.
